Primary Examiner — Samantha Wood*Assistant Examiner* — Vanessa Martinez(74) Attorney, Agent, or Firm — Tucker Ellis LLP; M. David Galin(57) CLAIM

The ornamental design for a lamp, as shown and described.

DESCRIPTION

FIG. 1 is front, left, top perspective view of a lamp showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines and de-emphasis in FIG. 3 are used to illustrate portions of the lamp that form no part of the claimed design.

1 Claim, 6 Drawing Sheets(56)
